UNITED STATES PATENT OFFICE.

WILLIAM H. BROWNELL, OF BROOKLYN, NEW YORK.

DESIGN FOR A PLAQUE-FRAME.

SPECIFICATION forming part of Design No. 15,850, dated February 24, 1885.

Application filed January 16, 1885. Term of patent 7 years.

To all whom it may concern:

Be it known that I, WILLIAM H. BROWNELL, of Brooklyn, in the county of Kings and State of New York, have invented and produced a new and original Design for Plaque-Frames, of which the following is a full, clear, and exact description.

Reference is to be had to the accompanying drawings, forming part of this specification, in which similar letters of reference indicate corresponding parts in both the figures.

Figure 1 is a face view of my design for plaque-frames. Fig. 2 is a cross-section of the same on the line $x-x$, Fig. 1.

15 A is a flat ring; B, an ogee molding formed on the inner edge; C, a concave quadrant molding formed on the outer edge; D, a vertical circular part extending downward from the bottom of the molding C, and E an external 20 bead at the bottom of the part D. The inner or bottom edges of the ogee molding B and of the head E are flush.

I claim—

1. The herein-described design for plaque-frames, consisting of a flat ring provided on 25 the inner edge with an ogee molding and another molding on the outer edge, substantially as herein shown and described.
2. The herein-described design for a plaque-frame, consisting of a flat ring provided on its 30 outer edge with a concave quadrant molding and at its inner edge with an ogee molding, substantially as shown.
3. The herein-described design for plaque-frames, consisting of a flat ring provided with 35 a molding on the inner edge, and the concave quadrant molding C, the straight part D, and the bead E on the outer edge, substantially as herein shown and described.

WILLIAM H. BROWNELL.
